Primary Examiner—Philip S. Hyder

[57] CLAIM

The ornamental design for a tool tote bucket, as shown and described.

DESCRIPTION

FIG. 1 is a front elevational of the tool tote bucket showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross-sectional view thereof taken along line 7—7 of FIG. 1;

FIG. 8 is a cross-sectional view thereof taken along line 8—8 of FIG. 1;

FIG. 9 is a front elevational view of an alternative embodiment thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a cross-sectional view thereof taken along line 15—15 of FIG. 9;

FIG. 16 is a cross-sectional view thereof taken along line 16—16 of FIG. 9;

FIG. 17 is another alternative embodiment thereof;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof;

FIG. 23 is a cross-sectional view thereof taken along line 23—23 of FIG. 17; and,

FIG. 24 is a cross-sectional view thereof taken along line 24—24 of FIG. 17.
